UNITED STATES PATENT OFFICE.

THEODORE VARNEY, OF PITTSBURG, PENNSYLVANIA, ASSIGNOR TO WESTINGHOUSE ELECTRIC & MANUFACTURING COMPANY, A CORPORATION OF PENNSYLVANIA.

ELECTRIC-TROLLEY-LINE CONSTRUCTION.

946,590.

Specification of Letters Patent. Patented Jan. 18, 1910.

Application filed June 4, 1906. Serial No. 320,140.

To all whom it may concern:

Be it known that I, THEODORE VARNEY, a citizen of the United States, and a resident of Pittsburg, in the county of Allegheny and 5 State of Pennsylvania, have invented a new and useful Improvement in Electric-Trolley-Line Construction, of which the following is a specification.

My invention relates to the construction of 10 electric trolley lines and particularly to such lines as are adapted for use with sliding or bow trolleys.

The object of my invention is to provide, in a construction of the class above indicated, 15 means for avoiding any possibility of damage to the sliding or bow trolleys or to the trolley conductors, at the junction of two or more lines.

Sliding or bow trolleys, such as are employed for high speed railway service, exert considerable upward pressure against the trolley conductors in order to insure a good electric contact therewith, and, consequently, the trolley line at and adjacent to the point 25 of contact with the trolley is raised a material amount. By reason of this fact, either the trolley itself or the line is liable to be damaged where two lines come together at a switch or turnout in the track, since the end 30 of the trolley contact shoe may become hooked over a line with which it is not in engagement.

In order to avoid the possibility of injuries of the aforesaid character, I provide a deflector which comprises a plurality of guard wires of considerable length which diverge from the junction of the two trolley lines, in substantially the plane of the two lines and are bent upwardly above this plane at each 40 end. Each one of these guard wires is adapted to be engaged by the trolley and are near enough together so that there is no possibility of the end of the trolley becoming entangled in the line.

45 In the accompanying drawings, Figure 1 is a plan view of portions of two trolley conductors and a guard constructed in accordance with my invention. Fig. 2 is a side elevation of the end sections, and Figs. 3, 4 and 50 5 are detail views of parts of the structure. Fig. 6 is a perspective view of a structure which embodies the subjects-matter of the other figures of the drawings. Fig. 7 is a 55 detail view corresponding to Fig. 3 by showing a modified structure.

Since a catenary form of line construction is often employed for use with sliding or bow trolleys, I have illustrated my guard in connection with such construction, but its use is, of course, not restricted thereto.

55 Referring to the drawings, trolley line conductors 1 and 2 are connected by a frog 3 and diverge therefrom at an acute angle with each other. These conductors may be supported in a well known manner from pairs of messenger cables 4 and 5 by triangular supports 6, such as are set forth and claimed in Patent No. 803,216, issued to Westinghouse Electric & Manufacturing Company, as assignee of Harry P. Davis 70 and myself.

A trolley deflector is provided between the conductors 1 and 2 and comprises a plurality of wires 7 each of which is clamped, at one end, to a relatively short angle iron 8, and, 75 at its other end, to a relatively long angle iron 9. The angle iron 8 is located at a short distance from the frog 3, between conductors 1 and 2, and is attached to two of the triangular supports 6 and also disposed substantially at right angles to the trolley conductors, at a short distance above them. The angle iron 9 is similarly disposed, but at a considerable distance from the frog 3. The angle irons 8 and 9 serve as anchors for 85 the guard wires 7 which are equally disposed between the trolley conductors 1 and 2. The wires 7 may be supported, at a plurality of intermediate points, substantially in the plane of the two trolley conductors by 90 means of spacers 10 which comprise cross rods or tubes 11 and U-shaped trolley hangers 12. The trolley hangers 12 are provided with projections 13 which are screw-threaded to receive pairs of trolley clamping 95 jaws similar to those ordinarily employed in trolley line construction. The lengths of the rods or tubes 10 are determined by the distance between the trolley conductors 1 and 2 at the points where they are located. 100 The horizontal plates 14 of the angle irons 8 and 9 are provided with holes through which U-shaped bolts 15 may be thrust for clamping the ends of the intermediate wires 7, and the vertical plates 16 are similarly 105 provided with holes near their ends to receive U-shaped bolts 17 which may be employed for attaching the angle irons to the triangular supports 6. Slots 18 are provided in the horizontal plate portion of the 110

angle iron 9 in order that the angle iron may be attached directly to the messenger cables 4 and 5 by suitable devices, such, for example, as U-shaped bolts 17^a, as indicated in Fig. 7, in case it is desired to support the ends of the guard wires at a greater distance above the plane of the trolley wires than is indicated in the other figures of the drawings.

10. I claim as my invention:

1. In an electric line construction, the combination with trolley conductors forming a V-shaped junction, and supports therefor, of a plurality of auxiliary diverging guard wires located between the trolley conductors, and supporting cross pieces clamped to the ends of said wires and to said trolley supports.

2. In an electric line construction, the combination with trolley conductors forming a V-shaped junction, and supporting means therefor, of a plurality of diverging guard wires located between the trolley conductors, supporting cross-bars clamped to the ends of the guard wires and to certain trolley conductor supports, and intermediate cross pieces clamped to the guard wires and provided with trolley hangers.

3. In an electric line construction, the combination with trolley conductors forming a V-shaped junction, messenger cables, and trolley hangers, of a plurality of diverging guard wires supported by said cables and hangers between the trolley conductors and extending for a considerable distance in substantially the plane of the trolley wires and gradually rising above said plane near their ends.

4. In an electric line construction, the combination with trolley conductors forming a V-shaped junction, of auxiliary diverging guard wires located between the trolley conductors, and supporting means for said guard wires.

5. In an electric line construction, the com-

bination with trolley conductors forming a V- 45 shaped junction, of auxiliary diverging guard wires located between the trolley conductors, spacing cross pieces for said guard wires, and trolley hangers attached thereto.

6. In an electric line construction, the combination with trolley conductors forming a V-shaped junction, messenger cables, and trolley hangers, of a plurality of diverging guard wires located between the trolley conductors and extending for a considerable distance in 50 substantially the plane of the trolley wires and gradually rising above said plane near their ends, supporting bars for said guard wires, and means for clamping said bars to certain of said trolley hangers.

7. In an electric line construction, the combination with trolley conductors forming a V-shaped junction, of diverging auxiliary 65 guard wires located between the trolley conductors, and supporting bars for said guard wires, spacing pieces for said guard wires, and trolley hangers attached thereto.

8. In an electric line construction, the combination with trolley conductors forming a V-shaped junction, of diverging auxiliary 70 guard wires located between the trolley conductors, messenger cables and hangers for supporting said trolley conductors, supporting angle irons for said guard wires clamped to certain of the trolley hangers and disposed substantially at right angles to the trolley conductors, U-shaped bolts for clamping each guard wire to the angle irons, intermediate spacing cross pieces, and trolley 75 hangers attached thereto.

In testimony whereof, I have hereunto subscribed my name this 31st day of May, 1906.

THEODORE VARNEY.
